CLAIM

The ornamental design for a raised planter as shown and described.

DESCRIPTION

FIG. 1 is a top perspective view of a raised planter; FIG. 2 is a front elevational view of the raised planter shown in FIG. 1;

FIG. 3 is a top plan view thereof;

FIG. 4 is a bottom plan view thereof; and,

FIG. 5 is a right side elevational view thereof.

The broken lines in the drawings depict portions of the raised planter and form no part of the claimed design. A rear elevational view is not shown because it is identical to the front side elevational view shown in FIG. 2. A left side elevational view is not shown because it is identical to the right side elevational view shown in FIG. 5.
